SPICE CAN DISPENSING CLOSURE

Thomas V. Bell, Cincinnati, and Fred Else, Urbana, Ohio, assignors to The Frank Tea and Spice Company, Cincinnati, Ohio, a corporation of Ohio

Filed Nov. 18, 1966, Ser. No. 4,729

Term of patent 14 years

(Cl. D9—275)

FIGURE 2 is a perspective view thereof, similar to FIGURE 1, but showing the closure in an open position;

The design is characterized by the end-to-end arcuate contour of the respective dispensing outlets and by the generally semi-circular configuration of the outlet lids in combination with the tabs thereon as shown.

We claim:

The ornamental design for a spice can dispensing closure, as shown and described.
